UNITED STATES PATENT OFFICE

LOUIS ALTERSON, OF NEW YORK, N. Y.

BUCKLE OR CLASP

Application filed July 29, 1931. Serial No. 553,725.

This invention relates to a buckle or clasp adapted for use on shoes, belts or in any other environment where it is desired to detachably unite the two ends of a strap. The object of the invention is to provide a buckle or clasp of the character described, which will be of simple and sturdy construction; which will securely, yet detachably, unite the two ends of a strap whether the same be a belt, **10** a shoe strap, or the like, and which will avoid repetitious adjustment of the strap through the buckle.

With most buckles it is necessary to move the strap or belt longitudinally through the **15** buckle frame each time that the belt or strap is opened and closed. This imposes frictional wear on the belt or strap, which after a short period of use becomes worn and shabby in appearance. With my improved buckle **20** or clasp, repeated longitudinal shifting of the strap through the buckle frame is unnecessary since the strap when once adjusted need not be again shifted. Wear and tear on the strap is thus avoided and a constant and uniform fit of the belt or strap is maintained.

In the accompanying drawings, which illustrate the preferred embodiment of my invention, Fig. 1 is a plan view of a buckle or clasp made in accordance with my invention **30** showing the same attached to a strap or belt; Fig. 2 is a view of the buckle or clasp, showing how the two elements of the same are separated to disengage the two strap or belt ends; Fig. 3 is a perspective view of the **35** buckle retaining member; and Fig. 4 is a sectional view on the line 4—4 of Fig. 1, looking in the direction of the arrows.

In the embodiment of my invention disclosed, the buckle or clasp is composed of **40** two main elements 1 and 2. The movable frame element 1 is mounted to be slidably adjusted on a strap or belt-end 8, said end 8 being passed under the side bar 4 on the member 1, and over the cross-bar 7 thereon and **45** thence under the other side bar 3. The buckle member 1 frictionally holds its position of adjustment on the strap 8 and may be manually shifted thereon as required, particularly when the member 1 is disengaged **50** from the retaining member 2. It will be seen from the foregoing, that the buckle member 1 is a frame composed of the two side bars 3 and 4, and integral end bars 5 and 6 united by the slightly depressed cross-bar 7 over which the strap-end 8 extends as was **55** just described.

The buckle retaining-member 2 forms a base and is clearly disclosed in Figure 3. The same has a flat central base portion 9 which rests on the face of the other strap end 17 and is secured thereto by stitches 16, staples, rivets or other fastening instrumentalities. At its opposite ends the portion 9 is widened into the parts 10 and 11, which parts are, at one end, bent upwardly as at **60** 19 and 20 respectively, and then bent to form the parts 12 and 13. The part 12 overlies the part 10 and co-operates with the same to form a U-shaped structure through which the strap-end 8 extends as shown in Figure 4, **65** 70 when the two buckle parts 1 and 2 are engaged. Similarly, the part 13 overlies the part 11 and co-operates therewith to form a U-shaped structure.

The part 13 is provided with a reduced **75** portion or flange 14 on which the side bar 4 of the buckle frame 1 is received. The inner edge 15 of this flange impinges against the face of the strap-end 8 as shown in Fig. 4, when the buckle parts 1 and 2 are engaged, **80** and acts to prevent the strap end 8 from shifting to the right of Fig. 4, or in other words from withdrawing. This flange 14 may if desired be slightly inclined downwardly as shown in Fig. 4 to impinge against **85** the strap with a greater or lesser extent of pressure.

From the foregoing, the operation of the buckle will be readily understood. The open position of the buckle is disclosed in Fig. 2. **90** The parts 1 and 2 are engaged by sliding the frame member 1 edgewise within the member 2, so that said frame 1 is located between the parts 12 and 13 of said retaining member, with the side bar 4 resting on the flange 14. **95** The strap-end 8 is, by the edgewise movement of the buckle frame, entered between the parts 10 and 12 and also between the parts 11 and 13, where the edge 15 of the flange 14 impinges against it and prevents the strap-end **100**

8 from withdrawing longitudinally. It also frictionally resists sidewise movement of the buckle frame 1 until the frame is manually moved sidewise to free the two parts 1 and 2 from one another.

5 The buckle structure provided is such that the strap need not be perforated. The frame member 1 when once adjusted on the strap-end 8 need not be again shifted. The two buckle 10 parts are readily freed or engaged by a simple sidewise movement of the frame 1 relative to its retaining member. When engaged in the manner herein described, these two parts remain securely interengaged and a simple, 15 sturdy and ornamental structure results.

15 What I claim is:—

1. A buckle having a base member provided with a pair of U-shaped arms, a strap-engaging frame movable edgewise into position between the arms, and a flange on one of the arms adapted to impinge against the strap engaged by the frame.

2. A buckle having a base member provided with a pair of spaced U-shaped portions, a strap-receiving frame removably lying between said U-shaped portions, with parts of said strap held by said frame extending through the U-shaped portions, and a flange formed on and projecting from one of the U-shaped portions and impinging against the face of the strap.

3. A buckle having a base member provided with a pair of U-shaped portions, a strap-engaging frame removably lying between the U-shaped portions, with parts of said strap extending through the U-shaped portions, and a flange formed on and projecting from one of the U-shaped portions, said flange supporting the frame and having its edge impinging against the face of the strap engaged by the frame.

4. A buckle having a base member provided with a pair of U-shaped arms, a strap-engaging frame movable sidewise between the arms with the strap engaged by said frame moved within the U-shaped arms, and means for frictionally resisting movement of the strap in one direction through the frame when said frame is located between the arms.

50 Signed at the city, county, and State of New York, this 28th day of July, 1931.

LOUIS ALTERSON.
